UNITED STATES PATENT OFFICE.

PETER BURKLECA, OF LIBRARY, PENNSYLVANIA.

SWITCH-THROW.

1,393,496.

Specification of Letters Patent. Patented Oct. 11, 1921.

Application filed April 22, 1921. Serial No. 463,728.

To all whom it may concern:

Be it known that I, PETER BURKLECA, a citizen of the United States, residing at Library, in the county of Allegheny and State of Pennsylvania, have invented new and useful Improvements in Switch-Throws, of which the following is a specification.

This invention relates to switch throws, and more particularly to a switch throw specially adapted for use in mines and similar places.

One of the main objects of the invention is to provide a switch throw of simple construction and operation which occupies but little space and may be readily positioned adjacent to the wall in a mine. A further object is to provide a switch throw which is yieldingly locked in position. Further objects will appear from the detailed description.

In the drawings:

Figure 1 is a top plan view of a switch throw constructed in accordance with my invention.

Fig. 2 is a front view of the switch throw.

Fig. 3 is a back view.

Fig. 4 is an underneath plan view.

An angular supporting plate 1 is secured in any suitable manner on the ends of ties A.

30 A guide rod 2 is secured to the inner face of plate 1 in parallel spaced relation thereto, this rod forming a track for travel of a grooved wheel 3 rotatably mounted in the lower end of the fork 4 which straddles rod 2 and is connected at its upper end by a tension spring 5 to a finger 6 pivoted in an operating lever 7 which is pivotally secured by a bolt or pin 8 between the outer face of plate 1 and a bracket 9 secured to the plate.

40 The lower end of this lever is reduced and rounded to form a finger 10 which passes through an elongated eye 11 provided at the outer end of outer arm 12^a of an angle lever 12. An arm 12^a operates between the base 1^a of plate 1 and a guide and supporting member 13 secured in spaced relation to the plate, this member being of substantially L-shape and having the inner end portion of its inner arm 13^a turned upwardly and out-

wardly to produce a substantially U-shaped bracket 14 which receives the angle portion of lever 12, this lever being pivotally secured in bracket 14 by a bolt 15. The inner arm 12^b of lever 12 receives a clip or bridle 16 pivoted at 17 to arm 12^b, this bridle being

adapted to receive a rod or other element for connecting arm 12^b to a switch point in any suitable or well known manner.

When lever 7 is thrown in either direction wheel 3 is caused to move along rod 2 in the direction of movement of the lever, and spring 5 is simultaneously tensioned. After the lever has been thrown beyond center spring 5 acts to complete the throw of the lever, and also to hold the lever in adjustment. In the event that the switch point to which arm 12 is connected is temporarily forced open the lever 7 will be rocked slightly so as to tension spring 5 and as soon as the force acting upon the switch point is removed the lever will be returned to its original position and will act through angle lever 12 and associated parts to return the switch point to its original position.

This switch throw has been proved by actual use under working conditions in a mine to be very practical and efficient while meeting all requirements as to safety and insuring that the switch will be held in proper adjustment. In addition, this device occupies a minimum of space and is particularly well adapted for use in mines and similar places where the saving of space is an important consideration.

What I claim is:—

1. In a device of the character described, a supporting plate, an operating lever rockably mounted on said plate, a rod mounted in spaced relation to one face of the plate and extending at opposite sides of the pivot of the lever, a member traveling on said rod, resilient connections between said member and the lever, a switch operating member, and operating connections between said member and the lever.

2. In a device of the character described, a supporting plate, a lever mounted on said plate, a rod secured in spaced relation to one face of the plate and extending at opposite sides of the pivot of the lever, a member traveling on said rod, a tension spring secured at its lower end to said member and at its upper end to the lever above the pivot thereof, and a member connected to said lever so as to be operated by the throw thereof.

3. In a device of the character described, a supporting plate, an operating lever pivoted on a horizontal axis on said plate, a substantially horizontally disposed rod se-

cured to the plate and extending beyond the pivot of the lever at opposite sides thereof, a member traveling freely on said rod, a tension spring having one end secured to said member and its other end secured to the lever beyond the pivot thereof, a switch lever, and operating connections between the operating lever and said switch lever.

4. In a device of the character described, 10 an operating lever pivoted on a horizontal axis, a member mounted for free horizontal movement in either direction beyond the fulcrum of said lever and held against vertical movement, a tension spring secured at one 15 end to said member and at its other end to the lever beyond the fulcrum thereof, a switch lever, and operating connections be-

tween said switch lever and the operating lever.

5. In a device of the character described, 20 a supporting plate, a lever pivoted intermediate its ends on said plate, a rockably mounted member provided with an elongated eye, the lever being provided with an element passing through said eye, a rod secured in spaced relation to one face of the plate and extending at opposite sides of the pivot of said lever, a member traveling on said rod, and a tension spring connected at its lower end to said member and at its upper 30 end to the lever above the pivot thereof.

In testimony whereof I affix my signature.

PETER BURKLECA.
